UNITED STATES PATENT OFFICE

FRANK OSCAR LEVI CHORLTON, OF BURY, ENGLAND

VARIABLE-SPEED DRIVE FOR PAPER-MAKING MACHINES AND THE LIKE

Application filed January 22, 1929, Serial No. 334,328, and in Great Britain March 13, 1928.

The invention relates to paper-making machines and such like machines made up of sections which require to be varied in speed relatively to the machine as a whole. For example, in the case of a paper-making machine, the sections referred to may comprise a travelling web of wire gauze on which the sheet is formed, rotary press rollers to consolidate the sheet and squeeze out some of the occluded water, a number of steam-heated rotating drying cylinders, a stack of polished rolls for finishing the surface of the sheet, and a reel upon which to wind the finished material. Variations in the contraction or expansion of the paper under treatment necessitate slight variations in the speeds of the sections relatively to the machine as a whole as stated.

Certain methods hitherto adopted for this purpose cannot be said to be entirely satisfactory, since in the case of large machines of the class named now employed the power to be transmitted introduces difficulties in those cases wherein the sections of the machine are driven by belting and oppositely inclined taper pulleys from one or more main driving shafts. As is well known the width of a belt which will run satisfactorily on taper pulleys is strictly limited and the power transmitted is therefore also limited. In addition, such driving arrangements take up a large amount of space; are wasteful of power, and make access to the driving side of the paper (or other similarly driven machine) difficult. The object of the invention is to provide an epicyclic gear forming one of many of such mounted on a continuous shaft common to them all, and sectionally driven. Said gear is not only a type by which the major portion of the power supplied is transmitted by toothed gearing to the in-driving shaft of the section concerned, but is constrained to revolve as one piece when belting of a belt drive of known kind used with the gear is at mid-position. In this way relative

speeds of the sections are suitably arranged, and each unit is readily removable from its position in the line shaft employed to permit of replacement by another unit in case of breakdown.

That is to say an epicyclic unit of gearing is provided for each section of the machine involved, said units are connected together by a shaft, or sections thereof, driven in suitable manner, such units being of a type wherein the major portion of the power supplied is transmitted through the epicyclics to the in-driving shafts of the sections named, only a minor portion of the power being utilized for varying the speed of said epicyclics, through the agency of a belt pair or drive driven from the shaft above named.

With reference to said drawings, Fig. 1 is a sectional elevation of epicyclic gearing referred to, or of the type named.

Fig. 2 is a portion of Fig. 3, excepting that the method of driving the main shaft is different.

Fig. 3 is a longitudinal elevation, more or less in diagram form, of sections of a paper-making machine, with unit drives applied thereto according to the present invention.

With reference to said drawings, *a* is the main driving shaft, and *b* a loosely mounted sleeve forming part of a wheel *c* in gear with dual forms of pinions *d*, loosely mounted on shafts *e* which shafts are fixed in a frame or box *h*. A pair of the pinions *d* engage a gear wheel *k* keyed to shaft *a*. Box *h* is in gear connection with a secondary shaft *m* by means of gear wheels *f* and chain *g*, the former being of equal pitch diameter, and which box is revolubly mounted as shown. Shaft *m* has attached to it a cone pulley *n* in belt connection with another cone pulley *o* of equal size keyed to shaft *a*. A clutch device *r* on the latter may be operated to connect sleeve *b* with sleeve *s* carrying worm *t*. This worm is shown in gear with worm wheel *q* attached.

to the in-driving shaft v of the supposed machine section to be driven.

In Figs. 2 and 3, a is the main driving shaft, and U are the several unit epicyclic drives of the type hereinbefore described.

In Fig. 3 the shaft a of continuous form is driven by means of a prime mover in the form of a steam engine indicated at w through belting x . In Fig. 2 an electric motor z is substituted, shaft a being in sectional form.

In Fig. 3 more particularly, the web of wire gauze of the paper-making machine is indicated at 1, a series of drying rollers or cylinders are shown at 2 and a stack of polished rolls at 3.

Each of such like sections of the machine are assumed to be driven through a unit U described.

Said units are not only capable of bringing about variability in speed as stated, but the variations are such as to be particularly applicable to paper-making and like machines, where the want of extremely slight adjustments of speed named may result in destruction of the material being produced in said machines.

With present-day forms of paper-making machines involving very considerable power to drive them, the need of sectional driving units without waste of energy to an excessive extent, becomes of increasing importance, especially having regard to the number of hours the machines are expected to run, with freedom from stoppages. In Fig. 1 is to be seen belt pulleys of equal ratios at the mid-position indicated of the belt, and also wheels f and g of equal sizes. Therefore for said mid-position the epicyclic gear employed will revolve as one piece. This means that for positions on either side of the mid-position named, the relative movements of the parts of the gear are not excessive. In this way excessive wear is avoided, or loss of energy prevented.

I claim:—

For use with a number of like gear units mounted upon a sectionally driven continuous driving shaft common to them all, for driving sections of a paper-making machine, an epicyclic gear comprising a driving element keyed to said driving shaft, pairs of pinions revolubly mounted on a revoluble frame or box, one pinion of each pair in gear with said driving element, the other pinion of each pair in gear with a gear wheel about said driving shaft, said wheel forming part of a sleeve loosely mounted on said shaft, said frame or box in gear connection with a secondary shaft by means of chain-connected sprocket wheels of equal pitch diameter, said secondary shaft being revolubly mounted parallel to the driving shaft beforenamed, and belt-connected cone pulleys of equal size oppositely mounted on said driving and sec-

ondary shafts respectively, the mid-position of the belting on the cone pulleys corresponding to the movement of the gear as one piece, motion transmitted from the sleeve herein referred to, to a gear wheel on the in-driving shaft of the paper-making machine, by means of a worm on the driving shaft, the sleeve of said worm being in clutch connection with the loosely mounted sleeve already described, as herein set forth.

In testimony whereof I have affixed my signature.

FRANK OSCAR LEVI CHORLTON.
